MACHINE FOR SEALING FILLED BAGS.

Emile C. St. Jacques and Robert H. St. Jacques,
Wareham, Mass.

Application July 1, 1949, Serial No. 102,456

3 Claims. (Cl. 154—42)

1

This invention relates to a machine for sealing filled bags, and particularly to a machine for sealing by heat and pressure filled bags made of cellophane or some other material that can be sealed in this manner.

One object of the invention is to provide a machine of this type which is so constructed that when its operation has been initiated by an attendant, it will automatically complete a cycle of operations, including feeding forwardly a conveyor loaded with filled bags to carry a bag to a sealing station and then bringing the conveyor to rest with the filled bag at said station, heat-sealing said bag while it is at the sealing station, and finally stopping all operations of the machine so that all the attendant has to do is to keep the conveyor supplied with filled bags and initiate each cycle of operations by some simple act like pressing a button.

A further object of the invention is to provide a machine of this type in which the feeding movement of the conveyor is initiated by the attendant, while the operation of the sealing means is initiated by the movement of the conveyor and is terminated by the sealing means itself.

A further object of the invention is to provide a machine of this type in which the conveyor and the sealing means are both operated from the same source of power, and means controlled by the movement of the conveyor functions to initiate the operation of the sealing means and also to bring the conveyor to rest, the termination of the operation of the sealing means being controlled by a moving part thereof.

While the invention is not concerned with the character of the material with which the bags are filled, yet the machine herein illustrated has been especially designed for heat-sealing cellophane bags that are filled with cranberries. The machine, however, is adapted for heat-sealing cellophane bags regardless of the character of the material with which the bags are filled.

In the drawings wherein we have illustrated a selected embodiment of the invention,

Fig. 1 is a front view of a machine embodying our invention.

Fig. 2 is a plan view thereof.

Fig. 3 is a sectional view on the line 3—3, Figs. 1 and 6, illustrating the heat-sealing means and the driving means therefor.

Fig. 4 is a fragmentary section on the line 4—4, Fig. 1.

Fig. 5 is an end view of the machine.

Fig. 6 is an enlarged vertical section through the heat sealing means on the line 6—6, Fig. 1.

2

Fig. 7 is a view illustrating the manner in which the conveyor operates the switches for starting the sealer and stopping the mechanism at the end of each cycle of operations.

Fig. 8 is a wiring diagram.

Our improved machine comprises an endless conveyor 3 by which filled bags such as indicated at 4 are fed to a sealing station where they are sealed and then delivered from said sealing station.

5 The conveyor 3 is mounted on a suitable frame 5 and it comprises a belt or band element 6 which has secured to and projecting from one face thereof a plurality of pairs of wings 7, 8, each pair of wings forming between them a pocket 9 to receive one of the filled bags 4. At one end the conveyor passes around a driving roll 10 by which it is driven, and at the other end it passes around the direction roll 11. The conveyor is arranged with

10 the endless band element 6 having a generally upright position so that the pockets 9 are open at the top and at the front side. The frame is provided with a platform 12 directly beneath the front run or front side of the conveyor and which forms the bottoms of the pockets. The rolls 10 and 11 are inclined backwardly from a vertical position as shown best in Figs. 5 and 4 with the result that the endless band 6, which forms the back of the pockets 9, has the same inclination and hence when a filled bag is placed in a pocket, it will not only rest on the platform 12, but will also rest against the band 6, and therefore there is no tendency for the filled bag to tip forwardly out of the open front side of its pocket.

15 The conveyor is driven from a suitable motor 13 which is connected to and operates a suitable reduction gear enclosed in a suitable gear box 14 and which is provided with a power take-off 15 from which is driven a shaft 16 connected by bevel gears 17 with the shaft 18 of the drive roller 10, said shafts 16 and 18 being mounted in suitable bearings 19 carried by the frame.

20 The power take-off 15 is connected to the shaft 16 through the medium of a clutch comprising a driving clutch element 20 fast on the power take-off 15 and a driven clutch member 21 mounted on the shaft 16 for rotation therewith but capable of movement axially thereof. The clutch is controlled by a clutch lever 22 pivoted at 23 and having pins 24 operating in a peripheral groove 25 with which the clutch member 21 is provided.

25 Movement of the lever 22 to the left in Fig. 1 will bring the clutch members into engagement and thus clutch the shaft 16 to the continuously operating power take-off 15, while movement of

the clutch lever to the right will disengage the clutch. The movement of the clutch lever for throwing the clutch into engagement and disengaging it is controlled by two solenoids, a clutch-closing solenoid 26 and a clutch-opening solenoid 27. These solenoids are mounted on the frame 5 and the upper end of the clutch lever 22 carries members 28 which form the cores for the solenoids.

When the clutch-closing solenoid 26 is energized, the lever 22 will be moved toward the left, Fig. 1, and the clutch will be thrown into engagement, while when the clutch-opening solenoid 27 is energized, the clutch will be disengaged. Means hereinafter described are provided by which the operator or attendant can cause the clutch-closing solenoid to be energized thereby starting the conveyor in operation and whereby the clutch-opening solenoid 27 will be energized to disengage the clutch when the conveyor has moved forward one step and has brought a filled bag to the sealing station.

The means for sealing each bag comprises a pair of electrically heated sealing irons 30 which are located above the conveyor and are normally in their spaced-apart relation shown in Fig. 3, thereby forming between them a passageway 31 through which the top portion of each bag passes as it is carried forward by the conveyor. Each sealing iron 30 is mounted on and carried by a carriage 32 which is mounted for movement in ways 33 formed in a supplemental frame portion 34. These carriages 32 are movable toward and from each other thereby similarly moving the sealing irons toward and from each other, the movement of the carriages and the sealing irons being transverse to the movement of the filled bags.

When any filled bag has been brought to rest at the sealing station, which is constituted by the space 31 between the sealing irons 30, the carriages 32 are moved toward each other to bring the two sealing irons against the top of the bag thereby pressing the bag top between the heated sealing irons, such operation resulting in sealing the bag because of the character of the material of which the bag is made.

The sealing irons 30 are preferably yieldingly carried by the carriages 32, each sealing iron being backed by springs 35, so that as the carriages 32 move toward each other, the sealing irons 30 will be brought into engagement with the bag and will subject the latter to pressure just before the carriages complete their inward movement, the springs 35 yielding during such final movement with the result that the heat-sealing pressure of the sealing irons on the bag will be maintained for sufficient time to effect the proper sealing operation.

The carriages 32 are given their movement toward and from each other by means of cams 36 which operate in openings 37 with which the carriages are provided. Each cam 36 is fast on a cam shaft 38 which is journaled in the supplemental frame portion 34, and the two shafts 38 are connected at their lower ends by means of a sprocket chain 39 which passes around sprocket wheels 40 mounted on said shafts 38.

These shafts 38 for operating the sealing irons are also driven from the motor 13, and for this purpose the reducing gear in the gear box 14 is provided with a second power take-off 41 which is adapted to be connected by a clutch comprising two clutch members 42, 43 with a shaft 44 that is connected by bevel gears 45 with one of the shafts

38. The clutch member 42 is a driving clutch member fast on the power take-off 41 while the clutch member 43 is a driven clutch member and is mounted on the shaft 44 for rotation therewith but is splined thereto so that it can move axially of the shaft for the purpose of engaging it with or disengaging it from the driving clutch member 42.

The clutch member 43 is controlled by a clutch lever 46 similar to the clutch lever 22, said lever 10 46 being pivoted at 47 to the frame and having lugs or pins 48 which operate in a circumferential groove 49 with which the clutch member 43 is provided.

The clutch-actuating lever 46 is also controlled by two solenoids, a clutch-closing solenoid 50 and a clutch-opening solenoid 51, said clutch-controlling lever 46 having at its upper end two members 52 which function as the cores for the solenoids 50 and 51.

20 When the solenoid 50 is energized, the clutch-controlling lever 46 will be moved to the right, Fig. 1, thereby starting the sealing mechanism in operation, and when the solenoid 51 is energized, the clutch will be disengaged.

25 The means for controlling the operation of these solenoids will be presently described.

The sealing irons 30 and their carriages 32 are mounted in the supplemental frame portion 34 for vertical adjustment so that the said sealing irons 30 can be raised or lowered as needed according to the size of the bags which are being filled and sealed. For this purpose the ways 33 in which the carriages operate are mounted on plates 53 which are vertically adjustable in the supplemental frame portion 34 by means of adjusting screws 54. These screws 54 are screw threaded through nut members 55 carried by an upper plate 56 of the supplemental frame 34 and the lower ends of the adjusting screws are swiveled in 40 the plates 53. Hence by turning the adjusting screws 54, the plates 53 with the carriages 32 and sealing irons thereon may be raised and lowered as desired.

The cams 36 are splined to the shaft 38 so that 45 said cams may move axially of the shafts when the sealing irons are raised or lowered.

In the operation of the machine, and assuming that all the pockets 9 between the pocket 9a and the sealing device are loaded with filled bags, the 50 attendant, after placing a filled bag in the empty pocket 9a, Fig. 1, actuates a starting switch 61, which may be a foot switch or a hand switch and which results in closing a circuit through and energizing the clutch-closing solenoid 26 thereby closing the conveyor clutch 20, 21 and establishing an operative driving connection between the motor 13 and the conveyor 3. The conveyor is thus started in motion and it moves forward one step to carry a filled bag into sealing position between the sealing irons 30.

Just before the bag to be sealed arrives at the sealing station, the moving conveyor operates another switch 60 which closes a circuit through the clutch-closing solenoid 50 thereby energizing 65 the latter and throwing the sealer clutch 42, 43 into engagement and starting the sealer. Immediately after the sealer has been started, the moving conveyor actuates a third switch 68 which opens the circuit of the clutch-closing solenoid 70 26 and at the same time results in closing a circuit through the coils of the clutch-opening solenoid 27 thereby energizing the latter and opening or disengaging the conveyor clutch 20, 21. The conveyor then comes to rest with a filled bag in 75 position to be sealed by the heated sealing irons.

It has been stated above that the sealer has been started in operation just prior to the stopping of the conveyor, and while the conveyor is at rest the sealer continues in operation and presses the open mouth of the bag between the two heated sealing irons thereby sealing the bag, the cams 36 returning the sealing irons to their retracted position after the bag has been sealed.

As the sealing irons 30 and their carriages 32 reach their retracted position, another switch 83 is actuated to establish a current through the clutch-opening solenoid 51 so that the latter becomes energized and operates to open the sealer clutch 42, 43 thus bringing the sealer to rest. This completes one cycle of operations.

The operator then places another filled bag in an empty pocket 9 which has been brought into loading position by the movement of the conveyor and again actuates the starting switch 61 when the above cycle of operations will be repeated.

In Fig. 8 there is shown a wiring diagram by which the clutch-closing solenoids and clutch-opening solenoids are controlled. In this diagram L1 and L2 represent the line wires of a supply circuit. The line wire L1 leads to the contacts 64 of the foot switch 61 and thence through the normally closed switch 68 and thence to the coils of the clutch-closing solenoid 26, the latter being connected by the wire connection 67 to the return line wire L2. So long as the foot switch 61 is open, which is its normal condition, the circuit through the solenoid 26 will be open, but when the operator depresses the foot switch 61, the circuit through the solenoid 26 is closed and the latter becomes operative to actuate the clutch-lever 22 and thus throw the conveyor clutch 20, 21 into operation. In order to maintain the circuit closed through the clutch-closing solenoid 26 after the operator has released the foot switch 61, there is provided a relay having a coil 62 which is connected across the line wires L1 and L2 in parallel with the coils of the clutch-closing solenoid 26, the relay coil 62 being connected to the line wire L1 by the circuit connection 99 and to the line wire L2 by the circuit connection 98. This relay includes an armature member 74 which is pivotally mounted at 69 and is normally held in its raised position by a spring 71 but which, when the relay coil 62 is energized, is swung downwardly to bridge a pair of contacts 70 in a circuit connection 73 so that when the relay coil 62 is energized, the circuit through the clutch-closing solenoid 26 will be maintained through the circuit connection 73 and the contacts 70 which are closed by the armature 74 even though the foot switch is released and is thus automatically opened.

When the conveyor has moved one step forward thereby to bring the mouth of a filled bag into sealing position between the sealing irons 30, the switch 68 is opened by the moving conveyor thereby opening the circuit through the relay coil 62 and through the clutch-closing solenoid 26 and de-energizing both said coil and the solenoid. To accomplish this each wing 1 of the conveyor has a button 78 and when each forward step of the conveyor has been nearly completed, a button 78 on one of the wings will engage an arm or shoe 79 and force the latter backwardly thereby opening the switch 68 with the result that the solenoid 26 and also the relay coil 62 will be de-energized. When the relay coil is de-energized, the spring 71 swings the armature 74 upwardly into engagement with two contacts 76 located in a branch circuit 76 which leads from the line wire L1 to

the clutch-opening solenoid 27, the latter being connected to the return line wire by the wire connection 77. Hence as soon as the relay is de-energized, the clutch-opening solenoid 27 becomes energized with the result that the conveyor clutch is disengaged and the conveyor comes to rest. Before the conveyor actually stops its movement, however, the button 78 which actuated the switch 68 has moved past said switch so as to allow said switch to be automatically closed.

Just before the said conveyor clutch is disengaged, a button 78 on one of the wings 1 closes the switch 80 in the circuit 81 which is connected across the line wires L1, L2 and which includes the coil of the switch-closing solenoid 50. The closing of the switch 80 energizes the clutch-closing solenoid 50, which as stated above, throws the sealer clutch 43, 42 into engagement and thus starts the sealer in operation, this occurring just before the conveyor has come to rest.

The teeth of the sealer clutch members 42, 43 are so formed that after said members have been engaged, they will be held in engagement by the transmission of the power from the driving clutch member 42 to the driven clutch member 43 even though the switch 80 is automatically opened after the button 78 by which it was closed has moved beyond the switch.

The starting of the sealer causes the cams 38 to rotate thereby first to advance the sealing irons and close them against the open mouth of the bag 4 thereby heat-sealing the latter, and then to retract said sealing irons into their retracted position shown in Fig. 3. Just as the cams arrive at the position shown in Fig. 3, a lug or wiper on one of the cams actuates and closes the normally open switch 83 in a circuit 84 which includes the coils of the clutch-opening solenoid 51 and which extends across from the circuit connection 76 to the line wire L2. The closing of the switch 83 will thereby energize the clutch-opening solenoid 51 and will disengage the clutch which operates the sealer whereupon the sealer will come to rest, thereby completing one cycle of operations.

When during the cycle of operations the conveyor has been brought to rest and while the sealing operation is being performed, the operator will place another filled bag in the pocket 9 which has been brought into the position indicated at 9a, Fig. 1, by the previous forward step of the conveyor, and as soon as the sealing operation has been completed and the sealer has been brought to rest, the operator will then actuate the foot switch 61 and thus start another cycle of operations thereby sealing another bag. This proceeding is repeated as each cycle of operations is completed and it will be observed that the operator has only to see that a filled bag is placed into each empty pocket as it comes into the position 9a and then at the appropriate time actuate the foot switch 61 to set the machine going to carry out one cycle of operations.

As stated above this invention is applicable for sealing filled bags regardless of the character of the material with which the bags are filled. For many purposes however it is desirable that each bag should contain a predetermined quantity of material, and if this is a requirement our sealing mechanism herein illustrated may be used in conjunction with a weighing and filling device adapted to deliver to a bag a predetermined weight of material.

While any suitable filling and weighing mechanism may be employed in connection with the

sealing mechanism herein shown, yet we have illustrated herein more or less diagrammatically a weighing and filling mechanism such as shown in our co-pending application Serial No. 102,455, filed July 1, 1949. Such a filling and weighing mechanism includes a hopper element 93, see Fig. 5, from which the material with which the bags are to be filled is delivered on to an endless conveyor 94, the latter in turn delivering the material to a weighing hopper 92 which is normally closed but which opens automatically to discharge its contents when a predetermined weight of material has been delivered thereto, the material delivered from the hopper 92 being discharged into a chute 90 having a delivery spout 91 adapted to be entered into the mouth of a bag 4 as shown by dotted lines Fig. 1.

With such a weighing and filling mechanism, the attendant will place the mouth of an empty bag over the delivery spout 91 and when the bag has received its predetermined weight of material, the operator will place it in the empty pocket which has been brought into the position 9a in Fig. 1.

We claim:

1. An apparatus for sealing filled bags comprising a conveyor for delivering filled bags singly to a sealing station, a motor, driving connections between the motor and the conveyor including a conveyor-operating clutch, a bag sealer at said sealing station for sealing each bag as it is delivered thereto, driving connections including a sealer-operating clutch between said motor and said sealer, manually controlled means for rendering operative the conveyor-operating clutch to start the conveyor in motion, conveyor-controlled means to disengage the conveyor-operating clutch when the conveyor has moved forward one step and a filled bag has arrived at the sealing station, whereby the conveyor is brought to rest, other conveyor-controlled means to render the sealer-operating clutch operative just prior to the stopping of the conveyor and means controlled by the sealer to disengage the sealer-operating clutch when the bag at the sealing station has 45

2. An apparatus for sealing filled bags comprising a conveyor for delivering filled bags singly to a sealing station, a motor, driving connections between the motor and the conveyor including a conveyor-operating clutch, a bag sealer at said sealing station for sealing each bag as it is delivered thereto, driving connections including a sealer-operating clutch between said motor and

said sealer, a clutch-closing solenoid for rendering the conveyor-operating clutch operative, manually controlled means for energizing said solenoid and thereby starting the conveyor in operation, 5 a clutch-opening solenoid for disengaging said clutch, conveyor-controlled means to energize the clutch-opening solenoid as the conveyor completes its forward step and delivers a filled bag to the sealing station, whereby the conveyor is brought to rest, and other conveyor-controlled means to render the sealer operative just prior to the stopping of the conveyor, and means controlled by the sealer to disengage the sealer-operating clutch when the sealing operation has been completed.

3. An apparatus for sealing filled bags comprising a conveyor for delivering filled bags singly to a sealing station, a motor, driving connections between the motor and the conveyor including a conveyor-operating clutch, a bag sealer at said sealing station for sealing each bag as it is delivered thereto, driving connections including a sealer-operating clutch between said motor and said sealer, a clutch-closing solenoid for rendering the conveyor-operating clutch operative, manually controlled means for energizing said solenoid and thereby starting the conveyor in operation, a clutch-opening solenoid for disengaging said clutch, conveyor-controlled means to energize the clutch-opening solenoid as the conveyor completes its forward step and delivers a filled bag to the sealing station, whereby the conveyor is brought to rest, a second clutch-closing solenoid for rendering the sealer-operating clutch operative, other conveyor-controlled means to energize the second clutch-closing solenoid just prior to the stopping of the conveyor whereby the sealer is set in operation, a second clutch-opening solenoid for disengaging the sealer clutch, and means controlled by the sealer to energize said second clutch-opening solenoid when the sealing operation on a bag has been completed.
